UNITED STATES PATENT OFFICE.

ROMEO POZZI, OF OAKLAND, CALIFORNIA.

HOT-AIR FURNACE.

1,217,126.

Specification of Letters Patent. Patented Feb. 20, 1917.

Application filed May 1, 1916. Serial No. 94,690.

To all whom it may concern:

Be it known that I, ROMEO POZZI, a citizen of the United States, residing at Oakland, in the county of Alameda and State of California, have invented new and useful Improvements in Hot-Air Furnaces, of which the following is a specification.

This invention relates to a hot air furnace.

The object of the invention is to provide a series of air chambers and passages which are so arranged within the furnace that practically every heat unit applied will be absorbed by the air and not wasted by escaping to the stack as is usually the case.

Further objects will hereinafter appear.

The invention consists of the parts and the construction and combination of parts as hereinafter more fully described and claimed, having reference to the accompanying drawings, in which—

Figure 1 is a central vertical section through the furnace.

Fig. 2 is a plan section on line 2—2, Fig. 1.

Referring to the drawings in detail, A indicates a cylindrical-shaped casing to the interior of which is secured an annular flange 2 upon which is supported a partition plate 3, which divides the casing into the upper and lower chambers indicated at 4 and 5.

Formed in the center of the plate 3 is an opening 6 to form a communication between the chambers, and formed on one side of the lower chamber is an opening 34 of the same height as the depth of the lower chamber 5. One side of the casing A is extended at 30 to lie tangential to the casing and a part 7 of the bottom of the casing is likewise extended to form with the extension 30 and the outer end 31 of a strip 10, the bottom, and two sides of a conduit connected to an air blower 8 which latter may be driven by an electric motor 9. The top of the conduit is formed by a cap 32 shown in fragment in Fig. 2. The strip 10 has its major portion disposed parallel to the side walls of the casing A and has its inner end 33 terminating opposite to the adjacent major part of the strip. The end 31 of strip 10 abuts the adjacent side wall formed by the opening 34, the conduit and strip 10 and the side walls of casing A forming a spiral air passage 11. The plate 3 seats on top of strip 10 and is shaped to abut the inner side faces of the side walls of casing A, the plate forming the top, and the bottom of casing

A, the bottom of the passage 11. This passage 11 imparts a swirling movement to the air delivered by the blower 8 and entering the lower chamber. The air then passes through the opening 6 and plate 3 up into the chamber 4 and is here permitted to escape through a plurality of distributing flues not here shown, which are connected with the discharge openings 12. Suspended by a plurality of arms 13 from the top of the furnace, and positioned directly above the opening 6 is a water pan 14, which may be filled from time to time through a filler cap 15. Positioned in the top of the furnace is a safety valve 16 and positioned below the bottom of the furnace is a heavy iron plate 17, which is provided for the purpose of evenly distributing and radiating heat to the lower chamber from a burner generally indicated at 18. Any form of gas or oil burner or coal furnace may be mounted below the furnace to provide the necessary heat but the most convenient arrangement employed is the form of gas burner shown having a valve within a casing V' operated by a hand wheel V. For the purpose of preventing the heat of combustion from escaping too readily around the sides of the furnace, a downwardly extending annular hood 19 has been provided. This is held in position by means of an annular flange 20 secured exterior of the furnace wall and is provided with a discharge vent 21, which may be connected with a stack or a pipe which will carry the fumes of combustion away from the furnace. The lower end of the hood is entirely open and in this manner permits a perfect circulation of air to support the combustion. Hood 19 has an opening 35 through which projects the parts 7, 30 and 31 as shown in Fig. 2.

The operation of the furnace, as a whole, will be as follows: The burner 18 is first lighted to heat the plate 17. This plate prevents the bottom of the furnace from being burnt and at the same time forms a means for evenly distributing the heat over the lower surface of the furnace. The motor 9, with connected blower 8 is then started, thus causing air to enter through the spirally arranged passage 11 formed in the lower chamber 5. The entering air is thus given a swirling movement and caused to pass over the entire heated surface of the furnace before it is finally permitted to escape through the opening 6 into the upper

chamber 4. The air is in this manner brought to the desired temperature and in escaping through the opening 6, strikes the bottom of the water pan where it heats the water sufficiently to permit this to slowly evaporate and pass off with the warm air through the discharge openings 12 with connected distributing flues not shown. The water pan may be filled from time to time 10 by removing the cap 15, thus preventing the discharging air from becoming too dry. The products of combustion escaping from the burner 18 collect in the hood 19 where they heat the sides of the lower chamber before they finally escape through the vent 21. An efficient, simple, compact hot air furnace is in this manner provided, which can be easily and economically operated by anyone. The safety valve 16 merely consists of a weighted cover supported by a pivot 16^a. This cover opens when the distributing flues are closed, and in this manner prevents the furnace from becoming overheated. Any suitable form of burner, 25 as previously described, may be employed and any means similar to the blower here shown, may be provided for the purpose of causing a perfect circulation of fresh air through the furnace. The air may be taken 30 from the exterior of the building or from the basement proper and as the furnace as a whole is comparatively low in proportion to its diameter, it can readily be seen that it can be conveniently installed in practically 35 any building.

The materials and finish of the several parts of the invention may be such as the judgment and experience of the manufacturer may dictate.

40 I wish it understood that various changes in form, proportions and minor details of construction may be resorted to within the scope of the appended claims, and that I do not wish to limit myself to the specific design and construction here shown.

Having thus described my invention, what I claim and desire to secure by Letters Patent is—

45 1. A hot air furnace including a cylindrical casing having a top and a bottom, a plate in the casing dividing same into an upper and a lower chamber, said casing having a peripheral opening of the same height

as the depth of the lower chamber and one side of the casing adjacent one side of said opening being tangentially extended therebeyond, a strip seated on the casing bottom and arranged at its outer end to lie parallel to said extension of the casing side and abutting the wall formed by the opposite side of the opening and having its major portion disposed within the casing and extending parallel to the casing sides and terminating in a free end which lies opposite to the major portion of the strip, said plate 60 being seated on top of the strip and abutting the casing sides and having a central opening, an outlet in the casing above the plate, a burner beneath the casing, said casing bottom being extended between the outer end of the strip and the extension of the casing side, and a hood secured exteriorly of the casing and having a depending flange formed with an opening through which the casing extension, the outer end of the strip 70 and said extension of the bottom of the casing project.

2. A hot air furnace including a cylindrical casing having a top and a bottom, a plate in the casing dividing same into an upper and a lower chamber, said casing having a peripheral opening of the same height as the depth of the lower chamber and one side of the casing adjacent one side of said opening being tangentially extended therebeyond, a strip seated on the casing bottom and arranged at its outer end to lie parallel to said extension of the casing side and abutting the wall formed by the opposite side of the opening and having its major portion 80 disposed within the casing and extending parallel to the casing sides and terminating in a free end which lies opposite to the major portion of the strip, said plate being seated on top of the strip and abutting the 85 casing sides, and having a central opening, an outlet in the casing above the plate, and a burner beneath the casing.

In testimony whereof I have hereunto set my hand in the presence of two subscribing 90 witnesses.

ROMEO POZZI.
